[57] **CLAIM**

The ornamental design for a flash attachment bracket for a camera, substantially as shown and described.

DESCRIPTION

FIG. 1 is an upper right front perspective view of a flash attachment bracket for a camera, showing my new design; and

FIG. 2 is a lower left front perspective view thereof.
The rear of the flash attachment bracket for a camera is a mirror image of the front.

*Fig. 1.**Fig. 2.*
